Primary Examiner — Ryan Harvey(74) *Attorney, Agent, or Firm* — Neal, Gerber & Eisenberg LLP(57) **CLAIM**

The ornamental design for a gaming machine, as shown and described herein.

DESCRIPTION

FIG. 1 is a front perspective view of a gaming machine of our new design.

FIG. 2 is an enlarged fragmentary front prospective view of the gaming machine of FIG. 1.

FIG. 3 is a front view of the gaming machine of FIG. 1.

FIG. 4 is an enlarged fragmentary front view of the gaming machine of FIG. 1.

FIG. 5 is a rear view of the gaming machine of FIG. 1.

FIG. 6 is a right side view of the gaming machine of FIG. 1.

FIG. 7 is a left side view of the gaming machine of FIG. 1.

FIG. 8 is a top view of the gaming machine of FIG. 1.

FIG. 9 is an enlarged fragmentary top view of the gaming machine base of FIG. 1; and,

FIG. 10 is a bottom view of the gaming machine of FIG. 1. The portions shown in phantom are not part of the claimed design.
